CIGARETTE DISPENSER

Russell L. Oliver, Philadelphia, Pa.

Application April 18, 1952, Serial No. 283,077

1 Claim. (Cl. 312—73)

1 My invention relates to a cigarette dispenser and the object of the invention is to produce an improved, practical, attractive, durable and inexpensive dispenser.

In the drawing:

Fig. 1 is a top plan view of a cigarette dispenser embodying the invention, certain parts being broken away to show details of construction.

Fig. 2 is a vertical sectional view taken on line 2—2 on Fig. 1.

The dispenser illustrated includes a pedestal formed of a base plate 10 and an inverted cup-shaped member 12 secured to said base.

On the wall 13 of the inverted cup-shaped member 12 there rests a dished member 14 having top wall 16 and a bottom wall 18.

The top wall 16 and the bottom wall 18 of the dished member 14 and the wall 13 of inverted member 12 are provided with registering openings 17 through which freely passes a rod 20 the upper end of which terminates in an enlarged finger piece 22 provided with a finger hole 24. The lower end of rod 20 is provided with nuts or other stop 26 to prevent disengagement of rod 20 from the lower dished member 14 and inverted member 12.

Above the dished member 14 is an inverted dished member 28 the wall 30 of which has an opening 32 through which rod 20 extends. The wall 30 of upper, inverted dished member 28 and the top wall 16 of lower dished member 14 are provided with registering openings 34 through which pass the arms 36 of a bail which also includes a transverse hand grip 38. The arms 36 are welded as at 40, or are otherwise secured to the wall 30 of the upper inverted dished member 28. The lower ends of arms 36 are freely movable through openings 34. One or more springs 42 are confined between the walls 16 and 30 to bias the upper dished member 28 and the bail carried thereby upwardly to the position shown in solid lines in Fig. 2.

The walls 16 and 30 are provided with vertically registering and circularly arranged holes 44 through which cigarettes 46 freely pass until they come to rest on the bottom 18 of lower dished member 14 as shown in broken lines in Fig. 2.

2

When the parts are in the solid line position of Fig. 2, the cigarettes project only slightly above the wall 30 of upper, inverted, dished member 28. To render the cigarettes more readily available, pressure is applied to the cross piece 38 of the bail to depress it to the broken line position of Fig. 2. This correspondingly depresses the upper dished member 28 and exposes a bigger portion of the cigarettes. This is most easily done by hooking the middle finger in opening 24 and applying the palm of the hand to cross piece 38.

It will be noted that the upper and lower dished members 14 and 28 and the bail carried thereby and the rod 20 are freely rotatable relative to the inverted cup shaped member 12 and the base 10.

What I claim is:

A cigarette dispenser comprising a lower member including a bottom wall and a top wall spaced from said bottom wall, said top wall having a first set of apertures therein through which cigarettes may pass to rest on said bottom wall, an upper member having a second set of apertures therein which register with said first set of apertures and through which cigarettes may pass, a spring biasing said upper member away from said lower member, a rod carried by said lower member and slidably engaging said upper member, means at the upper end of said rod to limit the upward movement of said upper member relative to said lower member to a distance such that the upper ends of cigarettes resting on said bottom wall will project slightly through said second set of openings, and a handle fixedly carried by said upper member and movable relative to said lower member, for moving said upper member downwardly to increase the extent to which the cigarettes project through said second set of openings.

RUSSELL L. OLIVER.
